FOLDABLE TABLE SET

Frank Hollentonder, Bridgeport, Conn.; now by
judicial change of name Frank Hollentonder

Application November 7, 1938, Serial No. 239,251

3 Claims. (Cl. 155—123)

This invention relates to a foldable table set comprising a table construction which may be opened to form a table to be used in the ordinary manner and then folded into a relatively small sized package for easy transportation in a car and carried, and including a set of stools or chairs which may be folded into a substantially flat condition and enclosed within the folded table construction so that they will not occupy any room outside the table and the table and chairs may be carried as a single package.

It is an object of the invention to provide an improved and simplified construction of the table and the chairs to accomplish the foregoing results.

It is another object of the invention to provide an improved construction and arrangement of such a set whereby the whole set may be folded and assembled into a very small package for easy transportation.

Another object is to provide an improved construction whereby the hinge means for mounting the supporting legs for the table when collapsed into the folded table will retain the folded chairs or stools within the table.

Still another object is to provide an improved handle construction which will when carrying the package have equal support on the different sections but when the table is set up will automatically move to a position out of sight under or within the table.

With the foregoing and other objects in view I have devised an improved construction illustrated in the accompanying drawings forming a part of this specification, it being understood, however, that various changes and modifications may be employed within the scope of the invention.

In these drawings:

Fig. 1 is a perspective view of the set folded and in condition for carrying as a single package;

Fig. 2 is a longitudinal section thereof;

Fig. 3 is a perspective view of a portion of the table showing it set up for use as such;

Fig. 4 is a plan view of the package or set opened up from the condition of Fig. 1 and showing the chairs or stools assembled within the sections of the table;

Fig. 5 is a longitudinal section of a portion thereof substantially on the line 5—5 of Fig. 4;

Fig. 6 is a side elevation of one of the stools or chairs set up in condition for use, parts being broken away to more clearly show the construction;

Fig. 7 is a front elevation of a chair in folded condition;

Fig. 8 is a view similar to Fig. 6 of the upper portion of the chair showing how the parts move to collapse the chair;

Fig. 9 is a side view of the chair folded;

Fig. 10 is a detail section substantially along the line 10—10 of Fig. 4;

Fig. 11 is a side view on an enlarged scale of the hinge mounting for the legs, a portion of the top being shown in section;

Fig. 12 is a similar view looking from the right of Fig. 11;

Fig. 13 is a view looking toward the bottom of Fig. 12;

Fig. 14 is an enlarged view of a portion of the carrying handle showing it shifted to the position it occupies when the table is set up and the handle is not used as a carrying means;

Fig. 15 is a view looking from the right of Fig. 14; and

Fig. 16 is a transverse section through the top edge portion of the folded set showing the handle in the carrying position.

25 This set comprises a table made in two sections hinged together so that they can be folded to lie side by side to form a closed case similar in appearance to a suit case, and can be as readily carried, and the sections form shallow compartments into which the supporting legs may be folded, and also each of which may hold a pair of collapsed chairs or stools which are effectively retained in position during carrying and as the set is opened up preparatory to setting up. This table with the chairs thus is foldable into a minimum of space and may be readily carried by one person, and it may also be readily carried in the trunk space or otherwise in an automobile and carried for picnic or camping purposes.

40 The table comprises two sections 10 each comprising a frame including side members 11 and 12 and end members 13 suitably connected together. These are preferably of wood of sufficient cross section to give a strong rigid construction.

45 In the present instance they are recessed at the inner top edges as indicated at 14 to receive the top panel 15 which may be wood of multiple ply construction, or a composition board, or any other material having the desired strength and freedom from warping. It will be seen from Figs. 2 and 5 that there is an open sided compartment at the inner side of this top panel and between the side and end members of the frame which is used to enclose the support-

ing legs and a set of folded stools or chairs as will presently be described.

The two side members 11 of the frame when the table is in the set up or open position lie side by side as shown in Fig. 4, and these two sections 10 are hinged together so that they may be folded to lie side by side with the open sides of the compartments facing each other as shown in Figs. 1 and 2. Fig. 3 shows a portion of the table in the set up or open position and as the hinge connection between the sections is at the under or lower sides of the members 11 it will be evident that when various articles are supported on the table or even with the weight of the table alone there is considerable strain on the hinges. I therefore meet this condition and am able to use large strong hinges by a novel construction. At the inner side of each of the end members 13 I place a reenforcing bar 16 which is securely fastened to the end member 13 by any suitable means such for example as screws 17, and extends to the inner side of the member 11. I then secure hinges 18 comprising long strong plates 19 to these reenforcing members 16 as shown in Fig. 4. It will be seen that this permits the use of large strong hinges and the long plates permit the use of sufficient screws 20 to securely mount the hinges and effectively withstand the weight of the table and the articles which may be placed thereon when the table is set up.

The table is supported on four legs 21 hinged to the sections 10 adjacent their outer corners. These legs are so attached to the sections that they may fold into the sections when the table is folded up for carrying, but when extended to the upright and supporting position are securely braced in all directions so as to make a strong rigid support for the table and with no danger of the legs collapsing during use. This improved mounting is also employed to retain the chairs or stools within the sections of the table when the table is folded. This improved table leg mounting is shown more clearly in Figs. 4, 11, 12 and 13. It comprises a metal frame or strap 22 of general angular shape secured in the outer corners of the section 10 by fastening to the frame members 12 and 13 by any suitable means such as screws 23. It will be seen this bracket or frame also helps to secure the frame members 12 and 13 together at the corner and in effect stiffen the frame. The table leg 21 is pivoted to one of the side arms of this bracket as indicated at 24 which is the arm secured to the outer or longitudinal frame member 12, and there is a toggle or linked brace 25 connecting this leg to the free end portion of the arm 26 of the bracket to which the leg is pivoted. This toggle brace comprises two sections 27 and 28 pivoted together at 29, and the section 27 is pivoted to the leg 21 at 30 and the section 28 is pivoted to the arm 26 of bracket at 31. At its inner end one of these members as 27 is provided with a lateral lug 32 to engage the edge of the other member 28 to form a stop to prevent the parts folding inwardly and to hold the members 27, 28 when the leg 21 is in the supporting position in a substantially straight line or with the pivot 29 slightly beyond a line joining the pivots 30 and 31 toward the pivot 24 to secure the supporting toggle effect. Also, to retain the elements in this position one of the members as 28 may be provided with a detent or recess 33 to receive a lug or bump 34 on the member 27 when they are in the extended

position to hold these elements in that position but permit them to be collapsed when desired to fold the leg into the table section. This effectively braces the leg in one plane which is parallel to the member 12 of the table top frame. In the other direction or at right angles to the frame member 12 there is provided another brace 35. This is secured to the leg 21 by any suitable means such as the screws 36 on the side of the leg extending transversely of the side to which the brace 35 is connected. At its other end this brace 35 is bent at substantially right angles to form a lug 37 and is pivoted to a similarly bent lug 38 on the end of the arm 22 of the bracket and extending inwardly at right angles thereto. The two lugs 37 and 38 are pivoted together at 39 which pivot is in alignment with the pivot 24 for the leg 21. This permits the table leg to swing about the pivot 24 the bracing arm 35 swinging with it about its pivot 39, but at the same time this brace 35 effectively braces the leg in a plane at right angles to the brace 25. Therefore it will be seen that the table leg when in the upright or supporting position is effectively braced in all directions. The brace 35 also performs a second function and that is of retaining the folded stools or chairs in the table top compartments as will presently be described.

It is desirable in order that the table may be folded to a minimum thickness and thus occupy a minimum of space that the stools or chairs be foldable to a completely flat condition, and it is also desirable that they be of light weight so as to facilitate carrying, but they should be strong and rigid to properly support the weight of the party using it. The construction of these stools is shown more clearly in Figs. 6 to 9. It comprises two pairs of legs 40 and 41 the legs of each pair being suitably spaced and one leg 40 of each pair is pivoted to the other leg 41 of the other pair intermediate their lengths as indicated at 42. The outer pair of legs 41 are connected by a transverse brace 43 and the inner pair of legs 40 are connected by a transverse brace 44, both braces 43 and 44 being below the pivots 42. The top or seat 45 is preferably made of sheet metal, although it may be of other material, having downwardly extending flanges 46 on three sides. The upper ends of the outer legs 41 are hinged to this flange adjacent the rear edge of this top or seat as indicated at 47. The upper ends of the inner legs 40 are connected by a cross bar 48 but are not secured to the seat member 45. They are merely located under the seat member so that when the legs are in the open position as shown in Fig. 6 the tops of these legs and the bar 48 are under the forward edge of the seat member 45 to support it. To yieldingly retain these members in this position a spring tongue 49 extends downwardly and inwardly from the front edge of the seat member 45 and may grip the cross bar 48 to hold it in the position of Fig. 6 during normal use, but by exerting inward pressure on the upper members 40 the bar 48 may be forced inwardly or released from this spring grip as indicated in Fig. 8, permitting the legs 40 and 41 to be folded into the same plane and a side by side position as shown in Figs. 4 and 9. After the legs are folded into this position the top 45 may be folded about the pivots 41 into the same plane as the legs as indicated in full lines Fig. 9 with the top or body portion of the member 45 lying against one edge of the legs 40 and 41 and with the flange 46 lying along side the outer side

of the leg 41. It will thus be seen the stool is folded into a perfectly flat position and occupies a minimum space and can be easily set up to the position of Fig. 6 and will be effectively held in this position against collapse when in use.

These stools are so proportioned that when in the collapsed or folded positions two of them may be placed in the compartment of each of the sections 10 as shown in Figs. 2, 4 and 5. It will be seen in Fig. 4 that they are placed in this compartment with one set of each of the pairs of legs 40 and 41 of each stool extending under the cross bars 43 and 44 of the other stool and therefore they hold each other within the compartment. It will also be seen that the supporting legs 21 are so mounted as to fold into these compartments to a position along and parallel with and at the inner side of the outer frame member 12 with the two legs lying side by side. To permit this one of the legs as 21a is mounted with the bracket 22 secured to the frame members 12 and 13. This permits the leg to be folded closely adjacent the frame member 12. The other leg 21b at the opposite corner is mounted by the same sort of hinge bracket but instead of the bracket 22 being secured to the frame member 12 a separate or frame member 50 is secured at the inner side of the frame member 12 and the bracket 22 is secured to the inner side of this member and the frame member 13. It will be seen this arrangement locates the leg 21b inwardly from the frame member 12 so that it may be folded into the compartment into the plane of the folded leg 21a but somewhat inwardly of the same. This permits using a thinner construction of table top section. It will be seen, however, that in both cases the brace 35 extends over a corner of the folded stool or chair, in this case a corner of the top or seat member 45, and thus when the stools are placed in the compartment with a pair of the legs 40 and 41 of each under the cross bars 43 and 44 of the other as indicated in Fig. 4 the table legs may then be folded down into the compartment to the position of Fig. 4. This folding of the legs down into the compartment carries the braces 35 to a position overlying the corner portion of each of the stools. Therefore the coaction of these braces and the more or less interlocking of the leg members of the chairs and the cross members 43 and 44 effectively retain these stools or chairs in the compartments and they cannot be removed until the chair legs 21 are swung from the folded position. This is important in that when the free edges of the sections 10 are lifted to fold them toward each other to close the case there is no danger of the stools falling out to interfere with this closing and there is also no danger of them falling out when the sections are opened preparatory to setting up the device until the user is ready to remove them from the sections.

There is also provided an improved handle or carrying means shown more clearly in Figs. 14, 15 and 16. This comprises a metal plate 51 pivoted or hinged at one edge to the under side of one outer frame member 12 as indicated at 52, there being one of these pivots or hinges at each end of the plate 51, although only that of one end is shown in Figs. 14 to 16. This permits the plate to swing from the position within the frame and compartment of the table section and out of sight as shown in full lines in Figs. 14 and 15 but permits the plate 51 to swing to a position at the inner side of and parallel with the frame

members 12 as indicated in dotted lines Fig. 15 and full lines Fig. 16. It will therefore be seen that this plate in this position overlaps both frame members 12 in the two sections 10 of the table. Secured to this plate 51 is a pair of supporting members 53 comprising heavy wire or rod each secured at its inner end to the plate 51 as shown at 54, and having a shank equal in length to about the thickness of the frame members 12 and bent at its outer end into a loop or eye 55 there being one adjacent each end of the plate 51, and then the carrying handle 56 is secured at its opposite ends to these eyes 55. Thus when the plate 51 is in the dotted line position of Fig. 15 or the position shown in Fig. 16 its shank extends through aligned notches 57 in the edges of the frame members 12 so that the handle 56 is at the outside. Then as the two sections 10 are folded together and secured by the two clasps 58 or other suitable securing and locking means the plate 51 lies under the two frame members 12. It will thus be seen that both these frame members and therefore both of the sections 10 of the table are equally supported and in the same manner by the plate 51 so that there is no more supporting strain on one section than on the other but both are equally and effectively supported. It is also preferred that when the legs 21a are folded into the compartments they will lie on the inner side of the plate 51 and hold it in the extended position of Figs. 4 and 16. I also prefer to provide on each of the hinges 52 a spring 59 tending to swing the plate 51 from the carrying position to the full line positions of Figs. 14 and 15 within the table top compartment. Thus as soon as the table is opened up and the legs swung to their supporting positions the plate 51 and the carrying handle are automatically swung by the spring in under the table top where it is out of sight and also out of the way.

It will be seen that this table set may be folded and assembled into a minimum of space for effective transportation in a car or other vehicle and may be easily carried in one hand to any desired location and then may be easily and quickly set up to give a strong rigid table construction with a full set of strong stools or chairs for use with the table.

Having thus set forth the nature of my invention, what I claim is:

1. In combination a foldable table including a top comprising a pair of hingedly connected sections, each section including a frame comprising side and end members and a top panel forming an open sided compartment, stools each having a sheet metal top and two pairs of legs pivoted together and one pair to the top and the other pair arranged to detachably engage the top, said legs being foldable into a single plane with the top along one side thereof so as to be placed in said compartments, said legs having cross members connecting the legs of each pair and when the stools are in the compartments adapted to be arranged with legs of each stool extending under a cross member of another stool so as to retain each other in the compartment, supporting legs for the table hinged to the sections adjacent the outer corners thereof and foldable into the compartments to lie side by side, and the hinge connection for each leg including an inclined brace connected to the leg and pivoted to its section and lying over the outer

end portion of a stool when the leg is so folded to retain the stools in the compartment.

2. In combination a foldable table including a top comprising a pair of hingedly connected sections, each section including a frame comprising side and end members and a top panel forming an open sided compartment, stools foldable into a substantially flat condition so as to be placed in the compartments and each having pairs of legs hinged together, cross members connecting each pair of legs and so arranged that when two stools are placed in a compartment at least some of the legs of each stool will extend under a cross member of the other stool, supporting legs for the table hinged to the sections adjacent the outer corners thereof and foldable into the compartments to lie side by side, and the hinge connection for each leg including a diagonal brace connected to the leg and pivoted to its section and arranged to lie over a stool when the leg is folded into the com-

partment to retain the stool in the compartment.

3. In combination a foldable table including a top comprising a pair of hingedly connected sections, each section including a frame comprising side and end members and a top panel forming an open sided compartment, stools foldable into a substantially flat condition and receivable in said compartments, supporting legs for the table hinged to the sections adjacent the outer corners thereof and foldable into the compartments, hinges for securing the legs each including an angular strap secured to two sides of the frame at the corner, means pivoting the leg to one arm of said strap, and a bracing member secured to the leg and pivoted to the other arm of the strap in alignment with the first pivot, said bracing member arranged to lie over a stool and retain it in the compartment when the leg is folded therein.

20

FRANK HOLLENTON.
